UNITED STATES PATENT OFFICE.

WILLIAM WALL TALBOT, OF ATLANTA, GEORGIA, ASSIGNOR, BY DIRECT AND MESNE ASSIGNMENTS, OF ONE-HALF TO SIDNEY H. BOYNTON, OF CHICAGO, ILLINOIS, AND ONE-HALF TO JAMES H. DOW, OF ATLANTA, GEORGIA.

LIFE GUARD OR FENDER.

1,111,772.

Specification of Letters Patent. Patented Sept. 29, 1914.

Application filed March 25, 1912. Serial No. 886,172.

To all whom it may concern:

Be it known that I, WILLIAM WALL TALBOT, a citizen of the United States, and a resident of the city of Atlanta, in the county of Fulton and State of Georgia, have invented certain new and useful Improvements in Life Guards or Fenders; and I do hereby declare that the following is a full, clear, and exact description of the same, reference being had to the accompanying drawings, and to the numbers of reference marked thereon, which form a part of this specification.

This invention relates to improvements in fenders, and more particularly to improvements in fenders adapted for use on automobiles and the like, to protect pedestrians and others from injury.

In fenders heretofore designed, with but few exceptions, no means have been afforded for picking up, or in any manner guarding from injury, a person who may have fallen before the car. In many instances also, it has occurred that the person having been knocked down by the car, is seriously injured by the car passing over him.

The object of this invention is to afford a construction capable of picking up and supporting a prostrate person to prevent injury by the car.

It is also an object of the invention to afford a construction affording an efficient buffer, capable of absorbing any ordinary shock of collision, thereby preventing injury to the car or to the person or object struck, and also equipped with a suitable apron capable of projection beneath the buffer bar to prevent the car passing over a person upon the road after, or at the time of such collision.

It is also an object of the invention to afford a construction whereby an apron is automatically projected into close proximity with the roadway when shock is imparted to the buffer bar.

It is an important object of the invention to afford a construction whereby the apron may be projected into operative position either by the operator or automatically by shock imparted to the buffer bar.

It is also an object of the invention to afford an exceedingly simple, compact, durable and strong device, capable of acting automatically to afford the desired protec-

tion, and also capable of manual operation independently of shock upon the buffer bar.

The invention (in a preferred form) is illustrated in the drawings, and hereinafter more fully described.

In the drawings: Figure 1 is a fragmentary side elevation with parts omitted and parts in section of a device embodying my invention, and the automobile to which the same is attached, the dotted lines showing the fender extended. Fig. 2 is an enlarged, fragmentary top plan view of the same. Fig. 3 is an enlarged, sectional detail of the means for yieldingly attaching the buffer bar to the car, showing the same in retracted position. Fig. 4 is an enlarged section on the line 4--4 of Fig. 3. Fig. 5 is a section taken on the line 5--5 of Fig. 3. Fig. 6 is an enlarged detail section of the mechanism for unrolling the apron downwardly into extended position. Fig. 7 is an enlarged section on the line 7--7 of Fig. 2. Fig. 8 is an enlarged, fragmentary section on the line 8--8 of Fig. 7. Fig. 9 is an enlarged inner face view of the buffer bar showing the same removed from the supporting and impelling means. Fig. 10 is an enlarged, fragmentary detail rear elevation of the device for supporting the apron upon the buffer bar. Fig. 11 is a section on the line 11--11 of Fig. 10, with parts omitted. Fig. 12 is a front elevation of the chassis and wheels of an automobile showing my improved device applied thereto.

As shown in the drawings: 1, indicates the front axle of an automobile; 2, a half elliptical spring secured thereon, as usual, and with which is connected the side frame chassis member or sill 3, of the car, in the usual or any suitable manner. Rigidly (but removably) secured upon the forwardly projecting ends of said side frame chassis members, is an outer clamping member 4, provided at its upper edge with a flange 5, as shown in Fig. 2, which extends thereover, and is provided at its upper corners with apertured bosses 6 and 7, and below the same with slotted openings 8, adapted to receive bolts 9, passing therethrough, which at their inner sides extend through metallic straps 10, affording the inner clamping plates whereby said outer clamping member is rigidly secured in place, as shown in

Figs. 1 and 2. The upwardly directed slots 8, in said clamping plate 4, adapt said clamping members for connection with any of the usual styles or forms of the side frame member of the automobile, or with the upper elliptical spring section, if the same be used at the front end of the car.

Rigidly (and, if preferred, integrally) connected with each of the clamping plates, 10 is a downwardly and rearwardly inclined cylinder 11, closed at its upper end and open at its lower end. Pivotally engaged at the lower, rear corner of said clamping plate 4, is a yoke 12, which projects forwardly beneath the axis of said cylinder, the other extremity of which projects rearwardly beyond its pivot 12^a and is directed upwardly and affords a laterally directed tail 13. Pivotally engaged upon the same pivot 12^a with 20 said yoke, is a toggle bar or link 14, which extends upwardly therefrom, and at its rear edge is adapted to bear against the tail 13, of said yoke to elevate the yoke, as shown in Fig. 3.

25 Journaled upon the upwardly directed arms of the yoke, is a transverse (and, if preferred, downwardly curved) link 15, having a centrally threaded aperture therethrough at its middle, in which is threaded 30 a thrust pin or rod 16, which extends upwardly in said cylinder at the axis thereof, and supported on the upper end thereof, is a cap 17, flanged at its bottom and upon which is secured a spiral pushing spring 18, the 35 upper end of which bears against the top of the cylinder, as shown in Fig. 5. Locking or jamb nuts 19 and 19^a, or any suitable means for rigidly engaging said thrust pin or rod 16, in adjusted position, are provided on the 40 lower end thereof.

Pivotally engaged at the front lower corner of said clamping plate 4, is a toggle bar or link 20, of equal length with the link or toggle bar 14, before described, and which 45 is held at all times in substantially parallel relation therewith by means of a connecting bar 21, pivotally engaged on the upper end of each, and provided at its forward end with an enlarged head spherically concave 50 on its under side, as indicated at 22, and affording a spring chamber 23, in its upper side, in which is engaged a spiral spring 24.

The buffering bar 25, comprises a downwardly facing channel bar having relatively 55 wide flanges, the outermost of which is convexly curved. Said buffering bar tapers and curves rearwardly at its extremities, and is secured in clamping members or brackets 26, at each side of the chassis of the machine, 60 each of which affords a fork to fit over said buffering bar, rigidly engaging the same therein. Each of said clamping members or brackets 26 is provided with a horizontally extended T slot on the rear side thereof, and 65 opening rearwardly therefrom, as indicated

at 27, in Figs. 3 and 9. A bolt 28, is engaged by its head in each of said T slots, and projects rearwardly therefrom and through a downwardly directed flange 29, which is rigidly secured thereto by means of the nut on said bolt. Integral with said flanges 29, and directed rearwardly therefrom, at the upper edge thereof, is an upwardly facing, spherically convex bearing head 30, supplemental with the cup 22 70 which is provided on the under side of the head on said bar 21, the two members thus affording a ball and socket pivot connection. Extending through said bearing head and cup and the spring chamber 23, is a bolt 31, 75 the threaded extremity of which extends through a cap 32, which closes the spring chamber, and through a plate 33, provided with an eye, as shown in Fig. 3, thus rigidly connecting said elements. Said plate 33 80 may be internally threaded to assist in engaging said bolt in place, in which event the nut on said bolt acts as a jamb nut to prevent loosening by vibration. This pivoted ball and socket construction permits 85 either end of the buffer bar to yield independently of the other under shock.

Engaged transversely in the channel of the buffering bar near each end thereof, is a bearing bar or plate 34, and journaled thereon by means of its pintles 35, is a spring or crank wound curtain roller 35^a having secured thereon a strong canvas, rubberized, or other suitable apron 36, connected at its inner end with the roller in any suitable 95 manner to afford sufficient strength for the connection. Said roller 35^a may be spring wound, or wound by means of a removable crank 36^a, shown in dotted lines in Fig. 2. Engaged on the outer edge or bottom of said 100 apron is a strong cylindrical rod 37. Rigidly secured on said apron rod 37, near each end thereof, is a downwardly and rearwardly curved arm 38, constructed of any suitable material (for example, light tubing) and 105 which, at its rear end, is pivotally engaged upon a suitable spring actuating device which augmented by gravity serves to project said arm downwardly against the tension of the curtain spring. Said spring 110 actuating means comprises a cylinder 39, open at its lower rearwardly directed end, and provided with an integral plate 40, which is engaged on the front axle by means of the spring clamp, as shown in Fig. 1. 115 The upper forwardly inclined end of said cylinder is restricted to afford a peripheral, inwardly facing flange or head, and is apertured centrally. The rear end of the spring actuating arm 38 is journaled above and out 120 of alignment with the cylinder 39, upon the pintle 41, which extends through forwardly directed lateral flanges integral with said cylinder. The coupling 42, whereby said curtain actuating rod 38 is engaged on said 125

pintle, is provided on its under side (and out of alinement with the axis of the rod) 5 with a pintle 43, on which is pivotally engaged the outer end of a tension rod 44, the inner end of which is threaded, and extends within said cylinder, and is provided therein with an elongated flanged nut 45, threaded thereon, and a jamb nut 46. Seated on the flange of said nut 45, is a pushing spring 47, the upper end of which bears against the flanged head of the cylinder, the construction being such that when the apron is elevated to the position shown in Fig. 1 in full lines, the tension exerted on the tension rods 44, 10 by means of the spring 47, is sufficient to throw the apron actuating arms 38 downwardly to the position shown in dotted lines in Fig. 1.

Means are provided for normally supporting the apron rod 37, against the pull of the 20 apron actuating arms. For this purpose, as shown, a spring detent 48 is secured at the inner side of the buffer bar at about the middle thereof, and projects forwardly beneath the buffer bar, as shown in Figs. 10 and 11, and supports the apron rod thereon, releasing the same, however, when the buffer bar is driven rearwardly by a shock. Means are also provided for normally releasing the 25 apron rod to project the apron downwardly. For this purpose a ratchet wheel 49 is secured upon one end of the curtain roller, as shown in Figs. 7 and 8, and a pawl 50, engaged by a spring 51, acts to normally hold 30 said pawl in engagement with the teeth of said ratchet wheel. A downwardly extending tail 52 is provided on said pawl, and an adjusting screw 53 is secured through the rear side of the buffer bar to bear against 35 the tail of the pawl so that by retraction of the screw, the pawl will engage the ratchet but if the screw is turned or threaded inwardly, the pawl will be held out of engagement with the ratchet wheel. A bracket 54 40 is secured on the rear side of the buffer bar, and journaled therem are sheaves 55 and 56, around each of which is trained a line 57, which leads rearwardly to the operator's position and may be attached to any hand or foot 45 lever or in any manner adapted for manual engagement to permit the pawl to be actuated by the operator. Connected with said line 57, and leading forwardly to, and connected in the eye of the plate 53, is a line 58, 50 The length of such line 58, is such that the same is at all times normally slack as compared with the line 57; in consequence, when the line 57 is pulled rearwardly, the pawl is first released, after which the end 55 of the buffer bar is pulled rearwardly by 55 means of the line 58, sufficiently to withdraw the detent 48 from beneath the apron rod.

The operation is as follows: From the construction described, it is obvious that the 60 buffer bar is at all times normally held for-

wardly in the position shown in Fig. 1, by the action of the spring 18, in the cylinder 11, which maintains a sufficient tension thereon at all times to prevent any tendency to tripping. When so adjusted, the apron 70 actuating arms 38 are supported against the tension of their springs 47, by the apron rod 37, which rests upon the spring detent 48, thus securely supporting the apron in its retracted or closed position within the buffer 75 bar, and maintaining such tension thereon as to prevent any tendency to rattle.

Should any object be now struck by the buffer bar, one or both ends thereof are driven rearwardly, in either event moving 80 the buffer bar centrally sufficiently to the rear to retract the detent 48 from beneath the apron rod, whereupon the apron is immediately extended by the downward pull thereon of the apron actuating arms 38, 85 under tension of their springs 47.

Should it be desired, for any reason, to project the apron downwardly, for example, to prevent injury to a child upon the street, the operator may pull the line 57, thereby 90 retracting the pawl 50, and swinging that end of the buffer bar sufficiently rearwardly to withdraw the detent 48, from beneath the apron rod, thereby projecting the apron 95 downwardly.

Should it not be desired to use the pawl and ratchet for normally assisting in supporting the apron in retracted position, the pawl may be thrown out of engagement with the ratchet by means of the adjusting screw 100 53. Should this be done, the apron may still be released manually, inasmuch as the rearward pull by means of the lines 57 and 58, acts to swing said end of the buffer bar sufficiently rearwardly to release the apron rod 105 37, from the detent 48.

Of course, it is to be understood that I have described but a preferred form of my invention. If desired, the full yielding, resilient, automatic action of the buffer bar 110 can be locked or unlocked by means of a pedal or lever near the driver's seat and controlling the pawl 50 and rod 37.

Numerous details of construction and application may be varied. I therefore do not 115 purpose limiting the patent to be granted on this application otherwise than necessitated by the prior art.

I claim as my invention:

1. A fender embracing a transverse buffing 120 bar yieldingly supported in advance of a vehicle, an apron normally concealed and engaged at one of its ends therein, a manually actuatable pawl and ratchet for normally supporting said apron in closed relation, means on the buffing bar for retaining said pawl out of engagement, and means for projecting and extending said apron downwardly.

2. A vehicle, a buffing bar yieldingly sup- 125

ported transversely thereon in advance thereof, a spring roller supported on the buffering bar, an apron rigidly engaged at its upper edge thereto, an apron rod in the 5 lower edge of the apron, a spring detent upon which said apron rod is supported and adapted to release said rod when said bar is actuated, arms hingedly engaged on the vehicle and rigidly connected with the 10 apron rod and acting to hold the apron rod from rearward movement when the buffering bar is actuated to release said apron rod from said spring detent and thereafter to project said apron downwardly, and manually operated means for actuating the 15 buffering bar independently of shock to release said apron rod for downward projection of the apron.

3. The combination with an automobile of 20 substantially horizontal spring impelled bars yieldingly supported on and above chassis frame at the front thereof, a buffering bar extending transversely of the vehicle, pivoted connections between the buffering bar and said 25 spring impelled bars permitting movement in either end of said buffering bar, a flexible fender normally concealed from view and engaged at its upper edge on the buffering bar, means normally supporting the same in 30 closed relation thereon, but releasable by shock on said buffering bar, and arms acting in part by gravity to project the curtain downwardly to open the same when the supporting means are released.

35 4. In a device of the class described a yieldingly supported buffering bar, a flexible apron secured and concealed within said buffering bar, means for projecting said apron downwardly into extended position, mechanism on the buffering bar adapted to be released by shock on the buffering bar for releasing said apron to extended position, and manually operated means also acting to release said apron to extended position.

45 5. In a device of the class described a transversely extending buffering bar comprising a downwardly facing channel bar curved rearwardly at its ends and tapered, a spring roller journaled in said buffering bar, a curtain 50 apron engaged along its upper edge on said roller, an apron rod engaged in the lower edge of the curtain, a forwardly facing detent on the rear side of the buffering bar acting to support said curtain rod when the curtain 55 is closed, and arms hingedly engaged on the vehicle frame and rigidly secured on the apron rod, and acting to hold the same against the retraction of said detent to release said rod when the buffering bar is actuated, and acting partly by gravity to project the apron downwardly to extended position when the detent is retracted.

60 6. The combination with a vehicle, of a buffering bar supported thereon transversely 65 in advance thereof, an apron connected with

the buffering bar and adapted to be projected downwardly when the buffering bar is actuated, plates secured between the axle and springs of the vehicle, a cylinder and apertured lug integral therewith, arms pivoted to said lugs and secured to the lower edge of the apron, and spring actuated rods extending into said cylinders adapted to project said arms downwardly.

70 7. In a device of the class described a buffering bar comprising a downwardly facing channel, an apron engaged at its upper edge therein and retractable thereinto, a pawl adapted to prevent unrolling of the apron, a screw adapted to throw said pawl out of engagement, a rod in the lower edge of said apron, a detent for supporting said rod therein, and means acting partly by gravity to project the apron downwardly to extended position when released from the 75 detent by movement of the buffering bar.

8. A device of the class described embracing, in combination with a vehicle, a buffering bar comprising a downwardly facing channel supported thereon in advance thereof to yield rearwardly under pressure or shock, a forwardly projecting detent on the rear side of the buffering bar, an extensible apron at its upper edge engaged in, and normally supported wholly within the channel, a rod in the lower edge of said apron adapted to be supported on said detent, apron actuating bars hingedly engaged on the vehicle below the buffering bar and rigidly engaged to the rod in the lower edge of the apron, springs 80 acting to throw the outer ends of said bars with the apron downwardly when said rod is released from the detent by shock, and manually operated means for releasing the 85 rod from said detent.

9. A device of the class described embracing a vehicle, a transverse buffering bar supported thereon to yield rearwardly under pressure or shock, plates attached to the axle of the vehicle, a cylinder integral with each of said plates, an apertured lug offset therefrom, an apron carried on said buffering bar, and spring actuated arms pivoted in said lugs adapted for projecting the apron downwardly to open position with rearward movement of the buffering bar.

10. In a device of the class described a buffering bar and an apron engaged thereon adapted to be projected downwardly to open position when the buffering bar is actuated, and spring impelled arms adjustable as to length hingedly connected with the vehicle and engaged to the lower margin of the apron and acting in part by gravity to impel the apron to open position when the buffering bar is actuated.

11. In a fender of the class described a yieldingly supported buffering bar, a roller thereon, a ratchet on the roller and a pawl pivoted to engage the same, means attached 110

to the pawl for manual actuation thereof, a screw threaded in the buffer bar adapted to lock said pawl out of engagement, an apron on the roller, and means extending and supporting the same downwardly when said pawl is retracted from said ratchet.

12. In a device of the class described, a buffer bar, a roller thereon, an apron secured on the roller adapted to be rolled up thereon, a ratchet on the roller, a pawl pivoted to the buffer bar, a spring adapted to press the pawl into engagement with the ratchet, a member attached to the pawl affording manual retraction thereof, a member for locking said pawl in retracted position, and means supporting said apron when unrolled.

13. In a device of the class described a yieldingly supported buffer bar, an apron adapted to be rolled up and supported thereon, a rod in the lower edge of said apron, means attached thereto to support the same fixedly in either retracted or extended position of the apron, a spring detent secured on the buffer bar adapted to engage said rod in the retracted position of the apron, and to release the same when the buffer bar is actuated, permitting extension of the apron.

14. In a device of the class described a vehicle, a buffer bar thereon, a flexible apron secured thereto, a plate secured to the vehicle, a hollow cylinder thereon, a spring actuated adjustable rod extending therethrough, an arm pivoted to said plate, and connected to said spring actuated rod, said arm being attached to the apron and adapted to project the same into extended position and afford support therefor.

15. In a device of the class described a buffer bar supported on a vehicle, an apron rolled within said bar, arms connected to said apron adapted to extend and support the same, a member secured to the vehicle comprising a spring actuated rod, pivots for one of said arms, said rod and arm being pivotally connected, and a lug integral with said member affording a stop for the movement of said arm.

In testimony whereof I have hereunto subscribed my name in the presence of two subscribing witnesses.

WILLIAM WALL TALBOT.
